US00D879812S

(12) **United States Design Patent** (10) **Patent No.:** **US D879,812 S**
(45) **Date of Patent:** **** Mar. 31, 2020**

(54) **DISPLAY SCREEN WITH A GRAPHICAL USER INTERFACE OF A CARD READER APPLICATION**

(71) Applicant: **GOOGLE LLC**, Mountain View, CA (US)

(72) Inventors: **Xiaohang Wang**, Millburn, NJ (US); **Marcus Quintana Mitchell**, New York, NY (US)

(73) Assignee: **Google LLC**, Mountain View, CA (US)

(**) Term: **15 Years**

(21) Appl. No.: **29/641,032**

(22) Filed: **Mar. 19, 2018**

Related U.S. Application Data

(62) Division of application No. 29/558,587, filed on Mar. 18, 2016, now abandoned, which is a division of application No. 29/459,294, filed on Jun. 27, 2013, now Pat. No. Des. 752,073.

(57) **CLAIM**

We claim the ornamental design for a display screen with a graphical user interface of a card reader application, as shown and described.

DESCRIPTION

The FIGURE is a front view for a display screen with a graphical user interface of a card reader application, showing the new design;

The broken lines in the drawings illustrate portions of the display screen with a graphical user interface of a card reader application that form no part of the claimed design.
